United States Patent Office.

JOHN DEEBLE, OF PLANTSVILLE, CONNECTICUT.

Letters Patent No. 66,956, dated July 23, 1867.

IMPROVEMENT IN FIFTH-WHEELS FOR CARRIAGES.

The Schedule referred to in these Letters Patent and making part of the same.

TO ALL WHOM IT MAY CONCERN:

Be it known that I, JOHN DEEBLE, of Plantsville, in the county of Hartford, and State of Connecticut, have invented a new Improvement in Fifth-Wheel for Carriages; and I do hereby declare the following, when taken in connection with the accompanying drawings and the letters of reference marked thereon, to be a full, clear, and exact description of the same, and which said drawings constitute part of this specification, and represent in—

Figure 1, a top view.

Figure 2, a rear view, and in

Figures 3 and 4, detached views.

This invention relates to an improvement in the manner of securing the two parts of a fifth-wheel together, whereby this part of the carriage is much strengthened, and the invention consists in the peculiar construction whereby the object of the improvement is attained; and in order to the clear understanding of my invention, as well as to enable others to construct the same, I will proceed to a description, as illustrated in the accompanying drawings.

A is the axle, B the rocker, C the reach, D the king-bolt, *a* the lower part, and *d* the upper part of a fifth-wheel, all constructed and arranged in the usual manner.

Considerable difficulty is experienced from the fact that the two parts of the fifth-wheel are in no way secured together, so that as soon as the king-bolt has become a little worn the wheel becomes more or less shakily, and the entire strain in drawing the carriage is brought upon the king-bolt, consequently increasing the wear upon that point. By my invention these difficulties are entirely overcome.

Upon the part *d*, and so as to be attached to the reach, I form a yoke, *f*, which carries a wheel, *l*, bearing up upon the under side of the part *a*, so as to hold the two parts firmly together; and in order to thus hold them without creating too much friction, I make the wheel *l* elastic, as seen in fig. 3, by forming a ring, *E*, of metal, with an elastic centre, *F*, upon a pivot, *G*, or an elastic face, *F*, and metal centre, *E*, as seen in fig. 4, so as to yield and press the two parts together only with the force of the elasticity of the material *F*. If the outer surface be metal, as seen in fig. 3, it should conform to the under surface of the part *a*. Thus the two parts are held firmly together at the "reach," and so that the connection at that point relieves to a great extent the strain and wear upon the king-bolt, and if, as often happens, the king-bolt is broken, this connection would hold the parts together and prevent the damage consequent upon such breakage.

I do not broadly claim a friction-roller, arranged so that the fifth-wheel will turn thereon.

Having thus fully described my invention, what I claim as new and useful, and desire to secure by Letters Patent, is—

Forming a connection and bearing of the two parts of a fifth-wheel at their intersection with the reach, by means of the yoke *f* and the wheel *l*, so as to support and hold the two parts of the fifth-wheel together; the whole constructed and operated substantially in the manner herein set forth.

JOHN DEEBLE.
